[57] CLAIM

The ornamental design for a steamer body, as shown and described.

DESCRIPTION

FIG. 1 is a top, rear and right side perspective view of a steamer body showing my new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The base plate in FIGS. 3-6 and the handle in FIG. 4 are shown in broken lines for illustrative purposes only and form no part of the claimed design. The undisclosed bottom is flat and unornamented.

FIG. 1

FIG. 2

FIG. 3

FIG. 4

FIG. 5

FIG. 6
